United States Patent Office.

W. C. WEDGE, OF CHICOPEE, MASSACHUSETTS.

Letters Patent No. 93,145, dated July 27, 1869.

OVEN.

The Schedule referred to in these Letters Patent and making part of the same.

To all whom it may concern:

Be it known that I, W. C. WEDGE, of Chicopee, Hampden county, State of Massachusetts, have invented a new and useful Rotatory Oven; and I do hereby declare that the following is a full and clear description thereof, reference being had to the accompanying drawings, and to the letters of reference marked thereon.

In the drawings—

Figure I is a plan view of my oven, and

Figure II is a partial sectional view, cut vertically through the oven.

The object of my improvements is to obtain economy of fuel, evenness of temperature, and convenience of operation.

These points I obtain, the construction is as follows:

The heating-space of the oven is confined between two cylinders, an inner one, A, and an outer one, B.

There are two chimneys, C and D, the one, C, in front, and the one, D, in rear, both in a direct line with the fire-box.

The heat travels around the cylinder A on each side, near its base, through flues E, which are of equal size and length on each side, and are perforated with holes, F, so that the heat can pass out into the baking-space G, between the two cylinders.

The middle of this space is occupied by a rotating baking-pan, H, which is formed in segments, and put together in the shape of a ring, around the inner oven wall A.

This ring rests upon friction-wheels I, and is guided by means of a rim, J, underneath, the rim J enclosing and guiding against the outer friction-wheels.

The baking-pan is revolved by means of a pinion, K, meshing with a circular rack, L, underneath the baking-pan, outside of the rim J.

The friction-wheel shafts, as well as the pinion shaft, have their bearings in the outer and inner walls, and the pinion-shaft is turned by power from the outside of the oven-walls.

The oven-door X is usually situated above the fire-box, and opens directly before the baking-pan.

A bonnet, M, is placed at this point, so that the current of air either from the oven or into it is interrupted as much as possible, and the baker thereby

prevented from being burned, and the oven from being unduly cooled when the oven-door is opened.

This bonnet may be set at any height to allow different thicknesses of bread to pass under its sides.

The method of arranging the dampers and chimneys allows the heat of the oven to be regulated to a nicety. Each chimney, C and D, is provided with a damper.

A pipe, N, communicates between the baking-space G and the chimney D, entering the latter just above the damper.

Now, when the dampers in both chimneys are open,

the draught is such that the fire kindles easily, heating the oven but little, but when both dampers are shut, the heat is forced out through the holes F in the flues E into the space G, finding its way into the chimney D, through the pipe N. Should the baker then desire to moderate the heat of the oven, he can open the damper in the chimney C, and thus produce a direct draught from the fire.

By this means, I accomplish my purposes in a simple and convenient manner, realizing economy, convenience of operation, and perfect results at little cost beyond that of ordinary masonry.

Now, having described my invention,

What I claim as new, and desire to secure by Letters Patent, is—

1. The construction of the oven herein shown, in which the baking-space G is contained between the inner and outer walls A and B, in which the revolving baking-pan H is also arranged in the manner substantially as set forth.

2. The combination of the walls A and B, chimneys C and D, flues E, and pipe N, the chimneys being arranged with dampers, and the parts being all constructed and arranged substantially as described.

3. In combination with the oven herein shown, the circular rotating baking-pan H; working upon friction-wheels, and operated by rack and pinion, substantially as shown.

4. In combination with the baking-pan H, the bonnet M, arranged as and for the purpose set forth.
